MATERIAL WORKING APPARATUS

Frank Martindell, Western Springs, Ill., assignor
to Western Electric Company, Incorporated,
New York, N. Y., a corporation of New York

Application September 21, 1940, Serial No. 357,741

9 Claims. (Cl. 164—110)

This invention relates to material working apparatus, and more particularly to a strip material locating and clamping device for punch press tools.

An object of the invention is to provide a simple and reliable material locating and holding device for material working apparatus, such as punch press tools.

One embodiment of the invention contemplates the provision of a strip stock locating and clamping device for punch press tools, in which the strip stock is pressed against a fixed gauge or abutment by the side expansion of a soft rubber block when compressed vertically by a plunger movable with the reciprocatory punch of a punch and die set.

A more complete understanding of the invention will be had from the following detailed description when read in conjunction with the accompanying drawing, in which:

Fig. 1 is a vertical sectional view of a punch and die set equipped with a strip material locating and clamping device embodying the invention;

Fig. 2 is a similar sectional view with the strip material shown clamped in position by the device, and

Fig. 3 is a plan sectional view taken on line 3—3 of Fig. 1.

The apparatus illustrated in the drawing comprises a stationary die member 10 and a reciprocatory punch member 11 adapted to cooperate with the die member to punch circular disks from a strip 12 of sheet material. The die is attached to a fixed platen or die supporting plate 14, only a portion of which is shown, and this plate may comprise or be attached to the stationary bed of a conventional punch press. The punch member 11 is attached to a reciprocatory platen or punch supporting plate 15, only a portion of which is shown, and this plate may comprise or be attached to the reciprocatory platen of the press. Above the die, the usual stripper plate 18 is provided, and on one side of the die opening a gauge plate 19 is interposed between the stripper plate and the die. Opposite the gauge plate, a movable clamping member 20 is provided for pressing the strip material against the gauge plate, whereby the strip material is properly positioned with respect to the punch and die members and is held against displacement during punching operations.

The clamping member is adapted to be shifted toward the gauge plate by the side expansion or deformation of a highly elastic soft rubber block

22 when the latter is compressed vertically by a plunger 23 attached to the punch supporting plate 15. The rubber block is supported upon the die supporting plate 14 adjacent the clamping member 20. It is confined on three sides by a vertical channel 25 fixed to the die supporting plate, and its remaining side is exposed for engagement with the enlarged outer end of the clamping member. The construction and arrangement are such that the soft rubber block is vertically compressed by the plunger 23 during each downward movement of the punch. This causes the exposed side of the rubber block to expand or bulge outwardly, as shown in Fig. 2. 10 The expanded or bulged-out portion of the rubber block engages and presses the clamping member toward the gauge plate, whereby the strip material is pressed against the gauge plate and is thereby properly located and held in position 15 for the punching operation. The parts are designed and arranged so as to insure proper positioning of the strip material by the clamping member just prior to each punching operation. As the punch supporting plate approaches the 20 end of its upward movement, the rubber block, by its own elasticity, resumes its normal shape shown in Fig. 1, thus permitting free movement of the strip material through the die.

It is to be understood that the apparatus here- 30 in illustrated and described is merely illustrative of one embodiment of the invention, which is capable of other applications within the scope of the appended claims.

What is claimed is:

- 35 1. In a material working apparatus, a material holding device comprising a fixed abutment and an elastic solid member adapted, when compressed in one direction, to expand in a different direction and thereby press the material against said abutment.
2. In a material working apparatus, a material holding device comprising a fixed abutment, a soft rubber block adapted, when compressed, to expand transversely and thereby press the material against said abutment, and means for compressing said rubber block to expand it in said direction.
- 45 3. In a material working apparatus, a movable material working element, and a material holding device comprising a fixed abutment, an elastic member having a portion which is adapted, when said member is compressed in one direction, to expand in a different direction for pressing the material against said abutment, and means for movable with said material working element for

compressing said elastic member to expand it in said last mentioned direction.

4. In an apparatus for working strip material, a material locating and holding device comprising an elastic member, means for compressing said member to expand a portion thereof, and a movable material engaging member actuated by said expanded portion.

5. In an apparatus for working strip material, a material locating and holding device comprising a rubber block, a reciprocatory member for compressing said block to expand a portion thereof, and a movable material clamping member actuated by said expanded portion.

6. In an apparatus for working strip material, a reciprocatory punch member, a cooperating die member, a gauge associated with the die member, a movable clamping member for holding the strip material against said gauge, and an elastic member adapted, when compressed, to expand 15 transversely and thereby actuate said clamping solid member.

7. In an apparatus for working strip material, a reciprocatory punch member, a cooperating die member, a gauge associated with the die member, a movable clamping member for holding the strip material against said gauge, an elastic 20

member adapted, when compressed in one direction, to expand in a different direction and thereby actuate said clamping member, and a plunger for compressing said elastic member to expand it in said first mentioned direction.

8. In an apparatus for working strip material, a reciprocatory punch member, a cooperating die member, a gauge associated with the die member, a movable clamping member for holding the strip material against said gauge, an elastic member having a portion which is adapted, when said member is compressed, to expand in a direction transversely of the direction of the compressing force and thereby actuate said clamping member, and a plunger for compressing said elastic member to expand it in said direction, said plunger being movable with said punch member.

9. In a material working apparatus, a material holding device comprising a fixed abutment, an elastic solid member adapted, when compressed in one direction, to expand in a different direction and thereby press the material against said abutment, and restraining means for constraining said elastic member to expand only in said 25 last mentioned direction.

FRANK MARTINDELL.
